(57) **CLAIM**

The ornamental design for a mobile device stand, as shown and described.

DESCRIPTION

FIG. 1 is a front perspective view of a mobile device stand showing my new design;

FIG. 2 is a rear perspective view thereof;

FIG. 3 is a front elevational view thereof;

FIG. 4 is a left side elevational view thereof;

FIG. 5 is a right side elevational view thereof;

FIG. 6 is a top view thereof;

FIG. 7 is a bottom view thereof;

FIG. 8 is a rear view thereof; and,

FIG. 9 illustrates the mobile device stand of FIG. 1 in a use condition.

The broken lines depicting environmental subject matter are for illustrative purposes only and form no part of the claimed design.

1 Claim, 3 Drawing Sheets
